ABSTRACT OF THE DISCLOSURE

Means for automatically opening and closing oppositely swinging hopper car doors while the car is in continuous motion wherein the doors are interconnected by an over-center toggle locking linkage actuated by trackside devices which first cause the doors to open and remain open during lading discharge, and then cause the doors to close and lock. Two modifications of the apparatus are disclosed which differ from each other both in the car toggle linkage and in the trackside devices.

This application is a continuation-in-part of application Ser. No. 494,797, filed Oct. 11, 1965, now abandoned.

The first of the two modifications referred to in the abstract comprises track-side means on one side of the track for actuating the toggle linkage to unlock and open the doors, second track-side means on the other side of the track to hold the doors open during lading discharge, and third means on the first side of the track for actuating the toggle linkage to close and lock the doors.

The second modification dispenses with the second means described above, leaving the first and third means only, both being on the same side of the track. Other differences are provided in the toggle linkage which interconnects the hopper doors and these are described in greater detail below.

Which one of the modifications is best applicable to a specific situation depends upon factors such as available space for the track-side devices, possible interference with other uses of the track, and the lock.

Further comprehension of the invention may be had from the following detailed description and accompanying drawings wherein like reference numbers refer to like parts:

FIGURE 1 is a side elevational view of the lower portion of a railway hopper car showing as much of the side of the car as necessary to illustrate one hopper with the doors in closed and toggle-locked position:

FIGURE 2 is a side elevational view similar to FIGURE 1, the doors being shown in fully opened position with the track-side actuating means in contact with the lifting crank arm:

FIGURE 3 is another side elevational view similar to FIGURE 2, the doors being shown as retained in a partially closed position by reason of the lifting crank arm riding on the surface of the track-side actuator. The view also illustrates the releasing and locking crank arm in engagement with the track-side camming device and further illustrates by conventional broken lines the position of the crank arms upon completion of the door closing operation:

FIGURE 4 is a fractional side elevational view of the hopper showing the doors in closed position and the track-side releasing means positioned in readiness for release of the mechanism and doors:

FIGURE 5 is a diagrammatic perspective view of the shaft and crank arms in relation to the track and door closing track-side actuators:

2

FIGURE 6 is a diagrammatic perspective view of the mechanism tripping actuator in relation to the railway track; and

FIGURES 7 and 8 are views similar to FIGURES 1 and 2, respectively, but illustrate the second modification of the invention in which the track-side device 40 is dispensed with and the various elements of the toggle linkage are constructed and arranged to assume operating positions different from the first modification in order to produce the same results despite the absence of device 40.

Referring now to FIGURES 1 to 6, the first modification of the invention is shown as applied in connection with a hopper assembly including oppositely sloping walls 10 which meet with longitudinally extending side walls, one of which is indicated at 11, to form a four sided hopper assembly. The open space bounded by the walls at the lower part of the assembly is divided into two discharge openings by an inverted V-shaped member 12 arranged transversely of the hopper car and paralleled to the hinge axes of the door. The lower margins of the side walls are reinforced by angle members 13 and the lower margins of the sloping end walls 10 are reinforced by means of downwardly flanged wall sections 14 in cooperation with angle members 15.

Hinge brackets 16 are carried by the side walls to which oppositely facing or swinging door assemblies 17 are pivotally mounted at 18. The door assemblies are preferably of scoop shape with side wall plates 19 and the doors proper comprising a body plate section 20 with upwardly extending flanges 21 on three sides to form a pan shaped structure. The fourth side of the plate 20 is deflected upwards as shown at 22. The underside of each door is reinforced by beam members 23, 24 and 25.

The doors are preferably operated by a jackknife type toggle locking mechanism generally indicated by 26. The mechanism includes an operating shaft 27 extending transversely of the hopper car and rotatably mounted on brackets 28 carried by one of the door assemblies. Operating arms 29 are non-rotatably mounted on shaft 27 near each end thereof and links 30 pivotally connect at one end at 31 with the distal end of the arms 29 and the opposite ends of links 30 pivotally connect with the oppositely facing door 17 through the medium of pivot 32 carried by an axially adjustable eyebolt 33 held in place by threaded nuts 34.

The toggle mechanism with the doors in closed position as seen in FIGURE 1 is adapted to assume an over-center locked position and to open out to a straightened position with the doors opened as seen in FIGURE 2. The operating arms 29 and links 30 are retained in extended position by interengaging shoulders or abutments 35 and 36 on the arms and links, respectively, which thereby also limit the opening of the doors to a predetermined amount.

Automatic operation of the doors by movement of the car is effected by crank arms 37 and 38, non-rotatably mounted on the opposite ends of shaft 27, in cooperation with track-side actuators 39, 40 and 41.

The crank arms 37 and 38 are preferably disposed in aligned relation and being rigidly united with the shaft, function as a tilting structure teetering about the axis of the shaft. The cranks of the crank arms 37 and 38 are each fitted with an antifriction roller 42 for cooperation with the track-side actuators as will be described.

The track-side actuators 39, 40 and 41 as seen in FIGURES 5 and 6, are located on opposite sides of the track 43 and in alignment with the rollers 42 for coacting therewith upon movement of the car.

The track-side actuator 39 includes a downwardly inclined ramp 50 adapted to bear down on roller 42 of crank arm 37 for releasing the toggle mechanism and opening the doors by movement of the car. The ramp 50 is preferably of appreciable length in order to exert

downward pressure on the doors even after the toggle mechanism has been released in order to assure positive opening movement of the doors.

The automatic closing operation of the doors by the trackside actuators 40 and 41 is effected in cooperation with the crank 37 and 38. Assuming the doors to be in open position as seen in FIGURE 2, the roller 42 of crank arm 38 rides on upwardly inclined ramp surface 44 of actuator 40, thereby swinging the crank arm upwardly to be retained in position by the roller riding on substantially horizontal surface 45 of actuator 40 for a predetermined extent of car travel according to the length of surface 45. The upward swing of arm 38 operates to tilt the opposite arm 37 downwardly to lie at a sloping angle and positioned to make contact with the actuator 41, whereby the doors are partially closed as shown in FIGURE 3.

The actuator 41 includes an upstanding wall 46 leading to an upper wall 47 which is pivotally mounted at 48 and held in raised position by spring 49. Upon continued movement of the car in the indicated direction, the wall 46 engages roller 42 of crank arm 37 and rotates the crank arm in a door closing direction and operates to cam the roller upwardly to ride over the wall 47 and thereby resiliently urge the toggle mechanism to closed position. The resilient retention of the upper wall 47 in elevated position fully compensates for variations in the height of the car such as may occur due to uneven track conditions or swaying of the car.

It will be observed that the pressure exerted on the crank arm 37 by the upstanding wall 46 is in a direction to assist the door closing movement. The automatic closing action of the doors is apparent by reference to FIGURE 3 wherein the forwardly extending crank arm means 38, after being displaced upwardly by the action of roller 42 along ramp 40, is maintained in said upwardly inclined position by rolling contact of roller 42 along horizontally extending surface 45.

The upward retention of the forwardly extending crank arm means operates to maintain the doors in partially closed position and also maintains the downwardly extending rearward crank arm means 37 in downwardly sloping position for a predetermined length of car travel or until such time as contact is made with upstanding wall 46 of actuator 41. The force of the contact made with wall 46 operates directly as a swinging force along arc 48 in addition to the indirect forces provided through the rotation of the shaft acting on the linkage along arc 49.

The impact of wall 46 on the mechanism and doors is mitigated by the equalizing effect provided by the connection with the opposite door and the smooth and gradual initiation of the closing movement provided along the inclined ramp 40.

Referring now to the second modification of the invention, the preceding description is generally applicable and the following will be for the most part devoted to describing the differences of this modification over the previously disclosed one.

In the arrangement now to be described, the trackside actuator 40 is omitted but its absence does not deprive the invention of its function. By modifying the elements of the toggle linkage to perform their functions in a somewhat different manner the same automatic operation of the hopper car is obtained as with the first modification.

The essential differences referred to are clearly evident by comparing the arrangements of FIGURES 2 and 8. It will be observed in FIGURE 8 that the arm 29' is appreciably longer than arm 29 of FIGURE 2. Furthermore while arm 29' is mounted on shaft 27', as in FIGURE 2, the portion of arm 29' between 27' and the axis of roller 42' is shorter, and the portion of arm 29' between 27' and the pivot 31' is much longer, than are the equivalent dimensions in the modification of FIGURE 2.

As a result, the arm 29' and the link 30' form an angle greater than 90 degrees when the doors are fully open and the limiting abutments 35' and 36' are in contact. In FIGURE 2, on the other hand, the arm and link lie in substantially a straight line.

It is also evident from inspection of the drawings, that the angular arrangement of the arm and link of the toggle linkage as seen in FIGURE 8, provides a leverage pressure which will hold the doors open until roller 42' contacts the wall 46' without the need of an actuator 40. It is also evident that because the arm 29' passes through a shorter angular distance than arm 29 during door closing, the former will pass through the vertical more quickly than the latter thereby accommodating rapid door closing just as actuator 40 does, among its other functions.

In the drawings and specification there have been set forth two preferred embodiments of my invention as set forth above in the abstract. Although specific terms are employed, they are used in a generic and descriptive sense only, and not for purposes of limitation.

What I claim:

1. In a railway car having an opening for discharge of lading and oppositely swinging doors for closing the opening mounted to swing on axes extending transversely to the path of movement of the car, in combination:

(1) an operating shaft rotatably mounted on one of the doors to extend transversely to the path of movement of the car,

(2) operating arm means non-rotatably mounted on the shaft,

(3) linkage means connecting the operating arm means and the opposite door and adapted to assume an over-center toggle locked position to maintain the doors in closed position,

(4) said operating arm and linkage being adapted to unfold to a straightened position upon full opening movement of the doors,

(5) means for automatically opening and closing the doors by movement of the car comprising;

(a) oppositely extending crank arm means respectively disposed on the respective ends of the shaft,

(b) one of said crank arm means extending forwardly in juxtaposed relation to the operating arm means and,

(c) the other of said arm means extending rearwardly from the shaft,

(d) a downwardly acting wayside ramp adapted to engage the rearwardly extending crank arm means for releasing the toggle mechanism and initiating opening movement of the doors and

(e) an upwardly inclined wayside ramp adapted to engage the crank of the forwardly extending crank arm means when the doors are in opened position and swing said crank arm means upwardly thereby disposing the rearwardly extending crank arm means to lie at a downwardly sloping angle,

(f) a trackway extending from the upper end of the upwardly inclined ramp forming a runway coacting with the crank of the upwardly extending crank arm means for a predetermined extent of car travel and

(g) a wayside actuator having a cam-like contour presenting an upstanding wall merging into an upper wall and positioned with the upstanding wall lying in the path of the downwardly sloping rearwardly extending crank arm means and adapted to deflect the crank thereof to ride on the upper wall and rotate the shaft to toggle locked position.

2. The invention set forth in claim 1 wherein the upper wall of the cam-like wayside actuator is pivotally mounted and resiliently held in operative relation.

3. In a railway car having an opening for discharge of lading and oppositely swinging doors for closing the opening mounted to swing on axes extending transversely to the path of movement of the car, the combination comprising:

- (1) a rotatable shaft carried by one of said doors;
- (2) toggle linkage means movable to an over-center locking position for interconnecting and operating said doors including,
  - (a) arm means non-rotatably mounted at one end on said shaft ends,
  - (b) link means connecting the other end of said arm means with the oppositely swinging door,
  - (c) said arm means and link means being openable to an extended position to open and hold open said doors;
- (3) second arm means extending from at least one of the ends of said shaft;
- (4) track-side actuating means positioned in the path of movement of said second arm means for turning said shaft and operating said toggle linkage means to unlock, open, close, and lock said doors, and
- (5) said arm means and link means includes a pivotally connected arm and link having shoulders thereon for abutting each other to limit opening of the doors to a predetermined amount.

4. In the combination defined by claim 3, wherein said trackside actuating means consists of first means for unlocking and opening said doors and second means for closing and locking said doors, said first and second means being spacedly mounted along one side of said track.

5. In the combination defined by claim 3, wherein said trackside actuating means consists of first means for unlocking and opening said doors, second means for closing and locking said doors, said first and second means being spacedly positioned along one side of the track, and third means positioned on the opposite side of the track intermediate said first and second means for partially closing said doors.

6. In the combination defined in claim 3, wherein said pivotally connected arm and link form an obtuse angle of less than 180 degrees when said shoulders are in abutting relation.

7. In the combination defined by claim 3, wherein the pivotally connected arm and link lie in a substantially straight line when said shoulders are in abutting relation.

8. In a railway car having an opening for discharge of lading and oppositely swinging doors for closing the opening mounted on axes extending transversely to the path of movement of the car, the combination comprising:

- (1) a rotatable shaft carried by one of said doors,
- (2) toggle linkage means movable to an over-center locking position for interconnecting and operating said doors including:
  - (a) arm means non-rotatably mounted at one end on said shaft ends,
  - (b) link means connecting the other end of said arm means with the oppositely swinging door,
  - (c) said arm means and link means being openable to an extended position to open said doors;
- (3) second arm means extending from at least one of the ends of said shaft,
- (4) track-side actuating means positioned in the path of movement of said second arm means for turning said shaft and operating said toggle linkage means to unlock, open, close, and lock said doors,
- (5) means including shoulders for abutting to retain said second arm means at a predetermined downwardly sloping angle when the doors are in open position, and
- (6) said track-side actuating means for closing the doors having a cam-like contour presenting an upstanding wall merging into a pivoted upper wall and positioned with the upstanding wall lying in the path of the downwardly held sloping arm means and adapted to deflect the arm means to ride on the upper wall and rotate the shaft to toggle-locked position.

9. In the combination defined by claim 8, resilient means for maintaining the pivoted upper wall in raised position to compensate for variations in car body height.
